UNITED STATES PATENT OFFICE.

CHARLES WARREN, OF MILFORD, MASSACHUSETTS.

IMPROVEMENT IN INHALING APPARATUS.

Specification forming part of Letters Patent No. 41,244, dated September 13, 1864.

To all whom it may concern:

Be it known that I, CHARLES WARREN, a resident of Milford, in the county of Worcester and State of Massachusetts, have invented a new or improved apparatus for inhaling medicated vapors into the lungs and bronchial passages of a person; and I do hereby declare the same to be fully described in the following specification and represented in the accompanying drawings, of which—

Figure 1 is a side elevation, and Fig. 2 a vertical section, of the said apparatus.

My invention is for effecting inhalation of vapors by the nostrils rather than by the mouth of an individual.

In the drawings, A denotes a bottle or reservoir for holding the fluid medicament to be inhaled in a state of vapor and with air. This bottle or reservoir has an open neck provided with a cap or cover, B, which should fit closely on the neck, and be furnished with two vertical tubes, C D, extending upward from the said cap and open at their lower ends into the interior of the bottle. There is also a third tube, E, extending from the cap B and down into the bottle and nearly to its bottom, the said tube E being open at both ends, so as to allow air to be drawn through it when it may be immersed in a liquid contained within the bottle or reservoir. The upper ends of the two vertical tubes C D should be arranged at a proper distance apart for both of them to be inserted in the nostrils of a person. Furthermore, these nostril-tubes are supplied with an elastic air-tight valve, F, which may be a small sheet of vulcanized caoutchouc ar-

ranged on both tubes, and having them extended through it, and grooved, as shown at a a, so as to hold it in place. The said valve is intended, when the apparatus may be in use, to be pressed up against the nostrils or those parts of the nose immediately contiguous to their mouths, the same being to effectually close such mouths of such nostrils.

When the apparatus is charged with a medicated fluid and applied to the nose of a person in manner as explained, an inhalation by the nose will cause air to be drawn through the tube E and the fluid, and thence into and through the nostril-pipes and into the nostrils, bronchial tubes, and lungs, the air while passing through the liquid being charged with the vapor thereof.

I do not claim an inhaling-vessel as made with an air-supply pipe and a single air-exhaust pipe; but

What I do claim as my improvement is—

1. The combination and arrangement of the two nostril-pipes C D with the vessel A, its cap B, and an induction-pipe, E, the same being substantially as described.

2. The combination and arrangement of the air-tight flexible valve F with the two nostril-pipes C D, and the vessel A, provided with a cap, B, or its equivalent, and an air-induction pipe, E, the whole being substantially as explained.

CHARLES WARREN.
